PARTITION FRAME

Ira Grayboff, Bloomfield, N.J., assignor to The Mills Company, Inc., Cleveland, Ohio, a corporation of Ohio

Filed Mar. 31, 1958, Ser. No. 50,257

Term of patent 14 years

(Cl. D13—1)

FIG. 1

Fig. 1 is a perspective view of a partition frame embodying my new design; and

Fig. 2 is an enlarged fragmentary sectional view approximately on the line 2—2 of Fig. 1.

The side of the partition unit not shown is substantially a mirror image of the side shown.

The drawings are shaded to show contrast.

I claim:

The ornamental design for a partition frame, as shown and described.
